FLIER CONSTRUCTION

Michael J. McHale, Scranton, Pa.

Application February 19, 1931. Serial No. 517,023

8 Claims. (Cl. 117—23)

This invention relates to improvements in flier blocks and more particularly to a flier block having a flanged foot of uniform diameter, and further, to improved bushings adapted to engage such feet.

Hitherto it has been proposed to use flier blocks having an offset flange at the bottom of the flier body adapted for engagement in a retaining bushing inserted in the top of a bobbin. The bushings are usually coaxial with the flier blocks, the spindle passing through the bobbin and the bushing, retaining the block locked in position by means of the engagement of the eccentric foot with the retaining shoulder of the bushing.

Such prior art installations are open to numerous objections, the chief of which are the increased cost in preparing the eccentric foot and the wear on the latter due to the single point contact of its surface which engages the retaining shoulder of the bushing.

It is an object of this invention to provide an improved bushing for insertion into bobbins.

Yet another object of this invention is the provision of an improved flier block and retaining means therefor, the latter being adapted for insertion into bobbins.

A further object of this invention is the provision of improved flier block retaining bushings adapted to provide a bearing surface of substantially 180° for the retaining flanges of the blocks.

These and other desirable objects and advantages of the present invention will be described in the accompanying specification and illustrated in the drawing, certain preferred embodiments being disclosed by way of illustration only, for, since the underlying principles may be embodied in other specific constructions, it is not intended to be limited to the ones here shown, except as such limitations are clearly imposed by the appended claims.

In the drawing like numerals refer to similar parts throughout the several views, of which

Figs. 1 and 2 are elevations partly in vertical section of bobbins mounted on their respective spindles and provided with flier blocks and associated retaining bushings;

Figs. 3 and 4 are top plan views of the bobbins shown in Figs. 1 and 2;

Fig. 5 is a vertical section taken on line 5—5 of Fig. 4.

Referring now to the drawing, there is disclosed the usual bobbins 1, mounted on spindles 2, which are tapered to engage the central axis of the bobbins. The spindles are provided at their upper portions with sections 3 of uniform diam-

eter which are adapted to support the freely rotatable flier blocks, 4, 5, shown in Figs. 1 and 2 respectively.

The improved flier blocks which form the essential part of the present invention are similar in construction to those shown and claimed in my applications Serial Nos. 458,212, and 489,401, filed May 31, 1930 and October 17, 1930, and are distinguished therefrom in that the bottom portion is provided with a retaining foot or flange 6 of uniform external diameter coaxial with the longitudinal axis of the block. By providing a retaining foot or flange of uniform diameter, it is possible to form the blocks in an automatic machine, and to avoid the usual step of punching or grinding off a portion of such flange to form an eccentric foot.

The blocks may be provided with any suitable type of flier wires 8, which are here shown as of the drop arm type, and which are retained in or on the blocks by any suitable means such as a knurled nut 9 or the integral slotted head 10, the details of which are shown and claimed in my applications above referred to.

The footed members or blocks 4, 5, are respectively adapted for engagement with retaining bushings 11, 12, which are inserted in the bobbins. These bushings comprise dished members, having skirted portions 13, adapted to engage suitable depressions 14 formed in the bobbins and are concentric with the axis of the spindles 2 for a purpose to be described more in detail hereinafter.

The novel bushings of the present invention are characterized by the provision of an improved or extended bearing surface or surfaces, as will now be described in some detail. Referring more particularly to Fig. 3, it will be noted that bushing 11 is provided with a non-circular aperture 17 in the end, which aperture may be substantially oval shaped, as shown. By inserting the foot 6 of a flier block into the aperture 17, the said foot may be introduced into the bushing and the block moved over so as to permit the section 3 of the spindle to pass therethrough and to hold it in bearing engagement with the shoulder or end portion 18 of the bushing.

It will be noted that with this construction the foot 6 is adapted for bearing engagement with the end 18 of bushing 11 over the major portion of a circle extending from point 19 around to point 20. This is in decided contrast to any bearing made possible by use of an eccentric foot where the bearing surface is of necessity considerably less than a semi-circumference. By this means substantially the entire bearing surface of member 6

is in bearing engagement with the retaining bushing 11 and due to the uniform distribution of the bearing forces it attains a longer life in use, consequent upon the uniform attrition or wearing down of the said member 6.

The members 11 may be formed of any suitable material such as copper, brass, steel or the like, and may be dished in any suitable punching apparatus and the apertures 17 formed by a simple punching operation. These bushings may be readily inserted or removed from the bobbins.

Referring now to Figs. 4 and 5, the improved bushing 12 is similar in construction to the bushing 11 and is provided with an aperture 21 which is concentric with the apron or skirt 13. In addition, there is provided in the end thereof a transverse slot 22 which is situated at one side of the circular aperture and is adapted to permit the insertion of the retaining flange or foot 6 of the flier blocks. The edge of the bushing end may be forced downwardly as indicated at 24 to permit the sliding of the block into position. This member has a central cut out portion 23 which defines one side of the aperture 21 of the bushing.

When the block is in place, the member 6 is in bearing engagement with the bearing portion 18 of the bushing over the major portion of a circumference, thus providing a substantially even bearing surface over its entire extent, in a manner substantially similar to that provided in bushing 11.

The member 12 may be formed in a manner similar to that used for member 11, a slot 22 being readily cut out or punched out of the end at the same time as the central aperture 21, or the circular aperture may be first punched out and then the transverse slot 22 formed in any suitable manner.

The improved bushings hereinabove described, in combination with the novel flier block construction, permit desirable economies both in manufacturing and operation, and the marked savings in fabricating costs are further enhanced by the savings permitted due to long wearing life of the improved blocks.

It will now be appreciated that there has been provided an improved flier block and retaining bushings therefor, which permit a marked saving both in installation and maintenance and which are characterized by simplicity of manufacture, installation and upkeep.

What is claimed is:

1. A flier assembly for spinning machines, including in combination, a flier having a concentric foot member of uniform diameter and mounted for rotation on a spindle, a bobbin on said spindle, and a removable bushing having

an ovoid shaped aperture in the end of said bobbin and in locking engagement with said foot.

2. A flier assembly for spinning machines, including in combination, a flier having a concentric foot member of uniform diameter and mounted for rotation on a spindle, a bobbin on said spindle, and a bushing having a non-circular aperture in the end of said bobbin in locking engagement with said foot.

3. A flier assembly for spinning machines, including in combination, a flier having a concentric foot member and mounted for rotation on a spindle, a bobbin on said spindle, and a bushing having a laterally slotted central aperture in the end of said bobbin in locking engagement with said foot.

4. A flier assembly for spinning machines, including in combination, a flier having a concentric foot member of uniform diameter and mounted for rotation on a spindle, a bobbin on said spindle and a bushing in the end of said bobbin having a circular aperture concentric with the axis of the bobbin and a slot at one side of said aperture, the bushing being in locking engagement with the foot.

5. A flier assembly for spinning machines, including in combination, a flier having a concentric foot member of uniform diameter and mounted for rotation on a spindle, a bobbin on said spindle, and a bushing in the end of said bobbin, comprising a dished member having an eccentric non-circular aperture, the bushing being in locking engagement with the foot.

6. A flier assembly for spinning machines, including in combination, a flier having a concentric foot member of uniform diameter and mounted for rotation on a spindle, a bobbin on said spindle, and a bushing in the end of said bobbin, comprising a dished member having a circular end and an oval shaped opening formed in said end, the major axis of said opening substantially coinciding with a diameter of the end, the bushing being in locking engagement with the foot.

7. A bobbin including a bushing adapted for insertion in the end thereof, comprising a dished member, a circular aperture in said bushing concentric with the central axis of the bobbin and a slot formed at one side of said aperture.

8. A bobbin including a bushing adapted for insertion in the end thereof, comprising a dished member having a circular end and an eccentric, oval shaped opening formed in said end.
